UNITED STATES PATENT OFFICE.

JOHN CRAIGMYLE, OF DANVILLE, ILLINOIS.

SWITCH-SIGNAL.

1,303,170.

Specification of Letters Patent.

Patented May 6, 1919.

Application filed February 11, 1919. Serial No. 276,354.

To all whom it may concern:

Be it known that I, JOHN CRAIGMYLE, a citizen of the United States, residing at Danville, in the county of Vermilion and State of Illinois, have invented certain new and useful Improvements in Switch-Signals, of which the following is a specification.

This invention relates to railway signaling, and more especially to signals adapted 10 to be mounted on switches; and the primary object of the same is to produce a signal of this kind for use in the daytime or the night time and which will clearly indicate at a distance whenever the switch has been left part way open instead of being entirely closed to establish the continuity 15 of the rails.

The invention consists broadly in making 20 the danger or red panels reëntrant instead of flat and disposing them quartering to the clear signals or panels, so that when the signal head is turned a little out of its strictly "clear" position, some of the danger panel is exposed.

25 The invention consists specifically in the application of this idea to both day and night signals, as set forth in the following specification and claims and as shown in the drawings, wherein—

30 Figure 1 is an elevation of the oscillating shaft of a switch, with both day and night signals mounted thereon, and

Figs. 2 and 3 are cross sections on the lines 2—2 and 3—3 of Fig. 1.

35 Fig. 4 is an enlarged vertical section on the line 4—4 of Fig. 1.

Fig. 5 is a perspective view of the day signal partly turned aside for purposes of illustration.

40 It is well known that numerous wrecks occur on account of this carelessness and efforts have been made to overcome it by providing switches which must be left either entirely open or entirely closed, but the 45 present invention is a switch signal adapted to be mounted on the upright rotating shaft of any switch, wherein said shaft is given a quarter revolution when the switch is moved from closed to opened position. The switch 50 is not illustrated herein, but I have used the letter S to indicate its upright shaft.

Referring now to the accompanying drawings, the day signal is a sheet metal structure whose sectional configuration is

perhaps best seen in Fig. 2. It includes a 55 sleeve 1 mounted upon the shaft or staff S and connected there by pins or keys 2, radial elements 3 projecting from diametrically opposite sides of said sleeve, flat panels 4 secured across the extremities of said elements and painted white on their outer faces which are oppositely disposed as shown, and two other reëntrant panels 5 painted red on their outer faces and connected at their outer edges with the white 60 panels at the corners 6, while their angular centers are connected with the sleeve 1 in any appropriate manner. These red panels which I call "reëntrant" are to be distinguished from the white panels which are 65 flat. The general configuration of the day signal is square, but by making each red panel of leaves, it gives it considerable area 70 additional to that of either white panel 4, and by making it reëntrant an advantage is 75 brought out which is set forth below. I will here say that it is not absolutely necessary that the two leaves of the panel be flat or the entire contour of the day signal be 80 square.

The night signal is a lantern broadly indicated by the letter L, and the details of the lantern itself are not essential. In its base plate is a socket 11 fitting removably over the squared upper end 10 of the shaft S 85 so that the lantern may be applied or removed but will rotate with the staff. The contour of the lamp box is best seen in Fig. 3. At opposite sides it carries two green lenses 14 corresponding with the white 90 panels of the day signal, and at the other two opposite sides quartering to these lenses it carries two reëntrant red panels 15 corresponding with the reëntrant panels 5 of the day signal. I call the red glass 15 "re- 95 entrant" because it is not flat. In Fig. 3, each glass is shown as dished or curved, rather than made in two flat leaves like the reëntrant panel 15 in the view above it. I wish it clearly understood that by the 100 word "reëntrant" I mean to include in either instance a panel which is not flat, but whose center stands farther inward than its edges. The lamp box surrounding and supporting the glasses may be of any appropriate construction, but in Fig. 4 I have shown at 16 how one lens 14 may have a handle by means of which it may be raised 105

so that access is gained to the lamp burner for manipulating the wick, etc. The glasses are shown as corrugated on their inner surfaces and the lenses 14 as ribbed on their inner 5 surfaces, but these details are not essential to the present invention. By preference I provide baffle plates 17 carried by the lamp box and rising above its top 18 so that the upper portion 19 of the lamp body is not 10 visible when looking at either lens 14 direct. The green lens 14 stands directly above the white panel 4 of the day signal, and of course both indicate a clear track. The red glass 15 stands above the reëntrant 15 red panel 5, and of course both indicate danger, as when a switch is open. The purpose of the present invention is to indicate when the switch is part way open, or in other words when it has not been completely closed. 20 The manner in which this is accomplished is perhaps best seen in Fig. 5. That is to say, when the switch is not completely closed the staff S will not have been turned to a position where it will carry the white panels 4 25 into planes directly at right angles to the length of the track. A person approaching from above or from below the view in Fig. 2 or 3 would see in the former case only a white panel and in the latter case only a green 30 lens, but a person approaching a signal which stood as shown in Fig. 5 would see not only the white panel 4 in the foreground but a considerable portion of one leaf of the red panel 5 which is now exposed beyond 35 the edge of the panel 4. Moreover, the surface painted red is substantially transverse to the line of vision because the panel 5 is reëntrant. The same is true of the inwardly curved red glass 15, although if the glass 40 is corrugated as shown, it may not be necessary to give as much curvature as the reëntrant panel 5. Yet at night when the switch is not quite closed, some portion of the red glass will be visible in addition to 45 the green light. Of course, when the switch is turned to an open position the shaft S will turn both the day and night signals so that only the red will show, and the green light at night, will be entirely hidden at 50 that time. Therefore, I prefer that the red panels of either signal shall be reëntrant rather than flat like the white panels 4. By day, the entire lantern will be lifted off the squared upper end of the shaft S to be re- 55 placed again in the evening.

The foregoing description and drawings have reference to what may be considered the preferred or approved form of my invention. It is to be understood that I may 60 make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A railway signal mounted on a rotary staff and including a flat white or safety panel and a reëntrant red or danger panel. 70

2. A railway signal mounted on a rotary staff and substantially rectangular in contour, its two opposite sides being flat and white to designate safety and its remaining two sides being reëntrant and red to designate danger, for the purpose set forth. 75

3. A railway signal mounted on an upright rotary shaft and including two directly opposite dished panels colored to indicate danger, and two other panels at 80 points quartering to the first two and colored to indicate safety.

4. A railway switch signal mounted on the upper end of a switch shaft which is given a quarter revolution in moving the 85 switch, said signal comprising a structure of substantially rectangular configuration whereof two diametrically opposite panels are colored to indicate safety and appropriately disposed with reference to the position of said staff, and the other two diametrically opposite panels at right angles to the first two are colored to indicate danger and are dished between their edges, for the 90 purpose set forth. 95

5. A railway switch signal mounted on the upper end of a switch shaft which is given a quarter revolution in moving the switch, said signal comprising a structure of substantially rectangular configuration 100 whereof two diametrically opposite panels are colored to indicate safety and appropriately disposed with reference to the position of said shaft, and the other two diametrically opposite panels at right angles to the first two are colored to indicate danger and are dished between their edges, for the 105 purpose set forth.

6. A railway switch signal mounted on the upper end of a switch shaft which is given a quarter revolution in moving the switch, said signal comprising a structure of substantially rectangular configuration whereof two diametrically opposite panels are colored to indicate safety and appropriately disposed with reference to the position of said shaft, and the other two diametrically opposite panels at right angles to the first two are colored to indicate danger and are each composed of two flat leaves forming a reëntrant angle and connected at their outer edges with the edges of the first named panels and at their inner edges with said staff. 110 115

7. In a railway signal, the combination 125 with an upright switch shaft having a squared upper extremity, and a day signal including a sleeve mounted on said shaft

below such extremity, and two white and two red panels respectively at right angles to each other; of a night signal consisting of a lantern having a socket in its bottom plate removably mounted on said squared extremity and two opposite green lenses and two diametrically opposite red glasses, the red glasses standing above the danger panels of the day signal, and both glasses and panels 10 being reentrant, for the purpose set forth.

8. In a railway signal, the combination with an upright switch shaft having a squared upper extremity, and a day signal including a sleeve mounted on said staff below such extremity, and two white and two red panels respectively at right angles to each other; of a night signal consisting of 15

a lantern having a socket in its bottom plate removably mounted on said squared extremity and two opposite green lenses and 20 two diametrically opposite red glasses, the red glasses standing above the danger panels of the day signal and being reentrant and corrugated, and the red panels of the day signal being each made in two leaves connected at their outer edges with the white panels and at their inner edges with each other.

In testimony whereof I affix my signature in presence of two witnesses.

JOHN CRAIGMYLE.
